(57) **CLAIM**

The ornamental design for a urinal, as shown and described.

DESCRIPTION

FIG. 1 is a top plan view showing our design thereof;

FIG. 2 is a elevated left side view;

FIG. 3 is a elevated front view;

FIG. 4 is a elevated right side view;

FIG. 5 is a elevated rear view; and,

FIG. 6 is a bottom plan view thereof.

The broken line showing of internal mechanical features is for illustrative purposes only and forms no part of the claimed design.
